CIRCUIT BREAKER

Cecil L. Brownlow, Bartlesville, Okla., assignor to
 Phillips Petroleum Company, Bartlesville,
 Okla., a corporation of Delaware

Application February 28, 1946, Serial No. 650,992

6 Claims. (Cl. 102-22)

1

The invention relates to seismographing and, more particularly, to breaking the electric circuit which fires the charge in case of accidental blowout of the firing wires from the drill hole.

In seismographing it is the custom to drill a number of holes in the ground throughout the area being prospected. Whenever this area contains a high tension electric power transmission line, one or more of the drill holes are apt to be rather close under the transmission line. Occasionally the wires carrying the current to the explosive in the hole are accidentally blown out of the hole and lodged over the high tension transmission line, causing danger to, and possible electrocution of, the operator firing the charge.

According to a preferred form of the present invention, an inexpensive snap-acting catapult or circuit breaker is placed in circuit with the explosive-firing wires. This catapult is controlled by a rope disposed over the mouth of the drill hole. A blow-out acting on the rope springs the catapult which automatically breaks the firing circuit and throws the ends of the wires well clear of the operator, and thus prevents high voltage from getting near the operator.

The principal object of this invention is to provide means for breaking a low tension circuit when danger of contact with a high tension circuit becomes imminent. Numerous other objects and advantages will be apparent to those skilled in the art.

The invention also consists in certain new and original features and combinations hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which the single figure represents, partly diagrammatically, a protecting system according to the invention.

In the following description and in the claims, various details will be identified by specific names for convenience, but they are intended to be as generic in their application as the art will permit.

In the drawings accompanying and forming part of this specification, certain specific disclosure of the invention is made for purposes of explanation, but it will be understood that the details may be modified in various respects without departure from the broad aspect of the invention.

In the drawing the drill hole is indicated by 10 and the explosive charge by 11. It will be understood that the hole 10 will be drilled to a

2

depth and at a diameter depending upon prospecting requirements. The hole may be surrounded by a bank 12 to protect it from surface water. It will be understood that a plurality of such prospecting holes are usually driven and fired, one at a time. The high tension power transmission line indicated by 40 is shown near the hole 10. The insulated low tension lead wires 13 extend from the circuit breaker 14 down into hole 10 to explosive 11. The circuit breaker 14 may be located on a truck (not shown) which may also carry the battery, or other source of electricity 15, and the key 16 for closing the circuit to explode the charge 11.

15 The circuit breaker or catapult 14 comprises a base 17 having a fulcrum pivot 18 pivotally supporting a throwing arm 19. The throwing arm 19 is biased to move upwardly under a tension spring 20 secured to the end of the arm 19 and to the base. Arm 19 is held down against the force of spring 20 by a catch or latch 21 having a shoulder 22 engaging over the throwing arm 19. A line 23 connecting the free end of catch 21 is disposed over the mouth of hole 10 and connected to a weight 26. If desired, the rope 23 and lead wires 13 may be twisted or tied together at their crossing point 27 although this is not necessary.

The throwing end of arm 19 has a seat comprising disc 28 and a pin 29 about which is 30 loosely disposed a closed loop 30 formed by twisting the free ends of both wires 13 together as shown. The free ends of wires 13 are engaged in spring clips 31 mounted on base 17. These clips 31 have binding posts 32 connected to wires 33 35 in circuit with key 16 and electric source 15.

In operation, the apparatus is connected as shown and the charge 11 is fired by the operator closing the key 16. Ordinarily the charge 11 goes off without blowing the wires 13 out of the hole 10. The results are recorded by seismographic apparatus (not shown) in the usual way.

However, should the explosive charge 11 accidentally blow out of the hole 10 carrying wires 13 out of the hole, a pull will be exerted on rope 45 23 which swings latch 21 to the right, releasing throwing arm 19 under the force of stiff spring 20. The device operates with a snap or "rat trap" action, the pin 29 moving upwardly with considerable force and velocity. This movement not only pulls the free ends of the wires 13 out of clips 31, but throws these wires and loop 30 clear of the base 14 and the truck on which the apparatus is mounted. These wires and loop 30 may be thrown as much as six to ten feet away 55 from the truck. Thus before the lead wires 13 can be thrown across the high tension transmission line 40, the low tension circuit is broken and the loop 30 and ends of the lead wires are thrown clear of the truck and operator, thus 60 protecting operator and truck from injury due

to high tension electricity from the transmission line 40.

Thus an inexpensive circuit breaker system is provided in which the looped wires may be said to form one pair of contacts and the spring clips on the base the other pair of contacts. This circuit breaker is operative to break the low tension circuit before it accidentally becomes subjected to dangerous high tension electricity. It not only breaks the circuit but projects the dangerous lead wires entirely clear of the firing apparatus and of the operator and truck. The force imparted to the wires is such that they act as relatively free or captive missiles or projectiles to the extent of being thrown very fast through the air away from the truck. The device is inexpensive to construct, easy to connect in circuit and use, and is reliable in operation.

While certain novel features of the invention have been disclosed herein, and are pointed out in the annexed claims, it will be understood that various omissions, substitutions and changes may be made by those skilled in the art without departing from the spirit of the invention.

What is claimed is:

1. A circuit breaker comprising a base, a throwing bar, a fulcrum on said base for said bar, a spring urging said bar away from said base, a catch pivoted to said base having a shoulder engaging over said bar to hold said bar against the stress of said spring, a pin carried by said bar, terminals carried by said base, a plurality of wires having their ends twisted together to form a loop with free ends, said loop being disposed over said pin and said free ends being connected to said terminals, and means for operating said catch to release the bar, said bar carrying said free ends away from said terminals and throwing said loop clear of said base.

2. A circuit breaker comprising a base, a throwing bar, a fulcrum on said base for said bar, a spring for moving said bar relative to said base, a catch engaging said bar to hold said bar against the stress of said spring, a seat carried by said bar, a terminal carried by said base, a conductor having a portion engaging said seat and having a free end connected to said terminal, and means for operating said catch to suddenly release the bar, said bar carrying said free end away from said terminal and throwing it as a relatively free missile clear of said base.

3. A safety system for use in seismographing and the like, comprising a base, a throwing bar, a fulcrum on said base for said throwing bar, a spring for urging said bar away from said base, a catch holding said bar against the stress of said spring, a seat carried by said bar, a terminal on said base, a lead wire connected to the charge in the drill hole, said wire having a portion engaging said seat and a free end connected to said terminal, a circuit connected to said terminal, said circuit including a source of electricity and controls for firing the charge, a line connected to said catch and disposed in proximity to said drill hole and adapted to pull said catch upon accidental blowout, said throwing bar, when released, tearing said free end from said terminal and throwing it clear of said base.

4. A safety system for use in seismographing and the like, comprising a base, a throwing bar, a fulcrum on said base for said throwing bar, a spring for urging said bar away from said base, a catch pivoted to said base and having a shoulder holding said bar against the stress of said

spring, a pin carried by said bar, terminals on said base, lead wires twisted to form a loop having free ends, said lead wires being connected to the charge in the drill hole, said loop being disposed over said pin with said free ends connected to said terminals, a circuit connected to said terminals, said circuit including a key and a source of electricity for firing the charge, a line connected to said catch and disposed in proximity to said drill hole and adapted to pull said catch upon accidental blowout, said throwing bar, when released, pulling said free ends from said terminals and throwing them clear of said base.

5. In a system of seismographing wherein an explosive charge is located in a drill hole in the ground, safety apparatus for firing said charge, said apparatus including firing wires leading to said charge, a circuit-interrupting device comprising a base, terminals on said base connected to said source on the one hand and to said wires on the other, a propulsion member, said circuit-interrupting device having a source of potential energy available to impart sudden movement to said propulsion member, a trip member for releasing said energy, said wires being disengageably disposed on said propulsion member, said circuit-interrupting device being located remote from said drill hole, a line connected to said trip member and disposed over said drill hole so as to be actuated by the accidental blowing out of said charge from said drill hole, said line serving to operate said trip member, whereby to cause said propulsion member to remove said wires from said terminals and to throw said wires clear of said base.

6. In a system for exploding a charge located in a drill hole in the ground, a catapult located remote from the drill hole, said catapult comprising a base, a throwing member mounted on said base, a power member in which potential energy is stored, said power member also being mounted on said base, said power member having driving engagement with said throwing member, a control member for suddenly releasing said potential energy to impart an abrupt movement to said throwing member; said system also comprising an electric circuit, said circuit including firing wiring leading to said charge and a source of electricity to explode the charge, said circuit including a conductor having a relatively movable portion engaging said throwing member and a relatively fixed portion engaging said base, an actuating member connected to said control member and disposed over said drill hole, said actuating member being actuatable by accidental blowing out of the charge from said drill hole, said actuating member operating said control member to release said potential energy, whereby the abrupt movement of said throwing member opens the circuit between said relatively movable portion and said relatively fixed portion, and throws said relatively movable portion, as a captive missile, entirely clear of the catapult.
